(57) **CLAIM**

The ornamental design for an LED lamp, as shown and described.

DESCRIPTION

FIG. 1 is a bottom view of a first embodiment of an LED lamp, showing our design;

FIG. 2 is a top view thereof;

FIG. 3 is a left side view thereof;

FIG. 4 is a right side view thereof;

FIG. 5 is a rear view thereof;

FIG. 6 is a front view thereof;

FIG. 7 is a rear perspective view thereof;

FIG. 8 is a front perspective view thereof;

FIG. 9 is a bottom view of a second embodiment of an LED lamp, showing our design;

FIG. 10 is a top view thereof;

FIG. 11 is a left side view thereof;

FIG. 12 is a right side view thereof;

FIG. 13 is a rear view thereof;

FIG. 14 is a front view thereof;

FIG. 15 is a rear perspective view thereof; and,

FIG. 16 is a front perspective view thereof.

The broken line showing in the Figures illustrates portions of the LED lamp and forms no part of the claimed design.
